UNITED STATES PATENT OFFICE.

JAMES EDWIN McDANIEL, OF COLUMBIA, SOUTH CAROLINA.

WEAR COMPENSATOR FOR JOURNAL BOXES.

Application filed July 23, 1920, Serial No. 398,408. Renewed August 4, 1922. Serial No. 579,766.

To all whom it may concern:

Be it known that I, JAMES E. McDANIEL, a citizen of the United States, residing at Columbia, in the county of Richland and 5 State of South Carolina, have invented new and useful Improvements in Wear Compensators for Journal Boxes, of which the following is a specification.

My invention relates to a self adjusting 10 solid wedge or an automatic compensator for taking up the wear in journal boxes.

An object of my invention is to provide 15 a simplified arrangement of wedges whereby by relative movement, the wedges will function to take up wear in the bearing.

A further object of the invention is to provide a ratchet device for locking the wedges in adjusted position.

Another feature of the invention is the 20 use of a yieldable device, such as a spring, the tension of which may be adjusted so that the proper amount of pressure may be continuously maintained on the bearing.

A still further object of my invention is 25 to provide a controlling mechanism for a bearing wedge that can be readily applied to existing arrangements so that the parts thereof are exposed to view, whereby excessive wear in the bearing may be readily 30 ascertained by simple inspection without the necessity of disassembling any of the parts.

Reference is made in the following specification to the accompanying drawings 35 which illustrate my invention as applied to a locomotive driving box.

In the drawings:

Figure 1 is a side elevation of my invention, part of the bracket device being shown 40 in section.

Figure 2 is a sectional view taken through the bracket above the auxiliary wedges.

Figure 3 is a vertical section taken through the base of the bracket and the bifurcated 45 portions of one of the auxiliary wedges.

Figure 4 is a view of a slightly modified form of my invention applied at right angles to the arrangement shown in Figure 1.

Figure 5 is a side elevation of a modified 50 form of my invention, parts of the frame and bearing wedge being shown in section.

Figure 6 is a longitudinal section through 55 a portion of the base of the bracket and one of the auxiliary wedges showing a novel form of ratchet device.

Figure 7 is a transverse section through the bracket mechanism and auxiliary wedges.

The numeral 10 designates the driving shaft which is mounted in the driving box composed of the upper section 12 and lower section 11. This driving box is slidably mounted between wearing plates 13 and 14 placed on opposite sides thereof, the plate 13 being fixed to the jaw 16 of the pedestal 15. The other jaw 17 of the pedestal is provided with an inclined inner surface 18 adapted to cooperate with the inclined surface of a wedge 19 which is interposed between the inner surface 18 and the wearing plate 14, the wearing plate 14 being preferably recessed throughout its length to provide a seat for the adjustable bearing wedge 19. It will be understood, however, that the adjustable wedge 19 may act directly on a flat surface of the wearing plate 14 or directly upon the driving box, in which case, the bearing plate 14 would be eliminated.

The jaws 16 and 17 are connected by the usual yoke or frame 20 apertured as at 21 for the passage of a threaded rod 28, the upper end of which is provided with a head 27 adapted to fit within a T-slot 26 formed in the lower end of the wedge 19 whereby said rod 28 is capable of moving the wedge 19 up and down. Secured to the frame 20 so as to depend therefrom is a bracket 22 that is detachably connected to the frame by means of screws or bolts 25. The lower portion of the bracket is bent over so as to firmly support a ratchet base plate 23, said base plate being apertured at 24 and said bracket being recessed in order to permit passage of one end of the rod 28 therethrough.

Adjustably secured to the threaded rod 28 is one of a pair of auxiliary wedges designated as 29, this wedge 29 being provided with a centrally downwardly projecting rib adapted to engage between the bifurcations 31 of a cooperating auxiliary wedge member 30. The bifurcations of the wedge member 30 are recessed along their upper inner edges so as to provide seats in which the wedge-shaped side surfaces of the wedge 29 may operate.

The lower sides of the bifurcations 31 are formed with ratchet teeth 33 adapted to coact with the ratchet teeth of the base plate 23. The end body portion of the bifurcated wedge 30 is formed with a T-slot 110

similar to the T-slot 26 of the bearing wedge 19, and in this slot is fitted the head 35 of a threaded rod 36 which is adapted to pass through an aperture 40 in one of the 5 sides of the bracket 22. Embracing the rod 36 is the nut 37, bearing collars 38, and the coil spring 39 which is compressed between one of the collars 38 bearing against the apertured side of the bracket 22 and the opposing collar 38 which may be adjusted in position by means of the nut 37.

The modified form of the invention shown in Figures 4, 5, 6 and 7 is similar to the form above described except that the bracket is 15 arranged at right angles to the frame instead of parallel therewith and corresponding parts of this modification have been marked with the reference characters similar to those applied to Figures 1, 2 and 3. However, a novel form of ratchet mechanism is applied to the bifurcated wedge 30' in which a recess 42 is formed in the body 30' so as to receive a projection 43 from the bifurcated ratchet plate 44 that is loosely mounted 20 in recesses 45 formed in the lower part of the bifurcations of the wedge member 30'. By this arrangement it is found that the weight of the loosely fitting ratchet plate 43-44 is sufficient for the teeth thereof to 25 effectually engage the ratchet teeth of the plate 23.

In operation, the tension of the spring 39 is adjusted to the pressure desired to be maintained on the driving box and it will be evident that any wear in the driving box will be 30 automatically taken up by means of this spring 39 forcing the bifurcated wedge 30 or 30' to the left, as shown in Figures 1 and 5, thus raising the wedge 29 and the bearing 35 wedge 19. At the same time the ratchet teeth of the bifurcated wedge will ride over the ratchet teeth of the plate 23 and thereby lock the wedge system from reverse movement. In this manner, the desired pressure on the 40 bearing will always be maintained, which pressure, of course, would allow the usual 45 sliding movements of the driving box in the pedestal jaws. It will be seen that owing to the open bracket 22 the relative positions 50 of the auxiliary wedges as well as the extent that the rod 36 extends beyond the side of the bracket 22 will be readily visible whereby the amount of wear in the bearing can 55 be readily ascertained by inspection.

While one of the jaws of my invention has 60 been described as having an inclined inner surface 18, it will be understood that this inner surface need not be an integral part of such jaw but may be composed of different 65 material from the material of the jaw and secured thereto by any suitable means. Also this device may be worked at right angles to the box and above the frame 20, allowing 70 bottom of wedge 19 to come directly in contact with the device. My invention may sug-

gest other equivalent constructions to persons skilled in the art but it is my intention to cover all such modifications and changes of construction that come within the spirit and scope of the appended claims. 70

I claim:

1. In combination with a bearing box and a frame in which said box is mounted, an adjustable bearing wedge associated with said bearing box, a bracket secured to said frame, and mechanism mounted in said bracket for controlling the position of said bearing wedge including an auxiliary wedge, and a spring-pressed rod extending from 75 said auxiliary wedge. 80

2. In combination with a bearing box and a frame in which said box is mounted, an adjustable bearing wedge in the frame arranged adjacent said bearing box, a bracket secured to said frame, and mechanism 85 mounted in said bracket for controlling the position of said bearing wedge including an auxiliary wedge, means yieldingly pressing said auxiliary wedge in one direction, and ratchet devices for preventing backward movement of said auxiliary wedge. 90

3. In combination with a bearing box, a pair of jaws having bearing plates between which said box is slidably mounted, one of said jaws having an inclined inner surface, 95 an adjustable bearing wedge interposed between said inclined inner surface and one of said plates, a pair of auxiliary wedges for adjusting the position of said bearing wedge, one of said auxiliary wedges being 100 connected to the bearing wedge, and means for moving the other of said auxiliary wedges. 105

4. In combination with a bearing box and a frame in which said box is slidably mounted, a bearing wedge cooperating therewith, a threaded rod detachably connected to said wedge and passing through an aperture formed in said frame, a pair of auxiliary wedges, one wedge of said pair engaging 110 the threads of said rod, the other wedge of said pair being bifurcated for embracing said rod, and a spring for adjusting the relative positions of said auxiliary wedges in accordance with the bearing pressure exerted by said box on the bearing wedge. 115

5. In combination with a bearing box and the frame in which said box is slidably mounted, a bearing wedge mounted within the frame and cooperating with said box, a rod detachably connected to said wedge passing through an aperture formed in said frame, a pair of auxiliary wedges, one wedge of said pair being adjustably secured to said rod, the other wedge of said pair 120 being bifurcated for embracing said rod, a bracket secured to said frame, spring means for pressing said bifurcated wedge in one direction and cooperating ratchet teeth on said bifurcations and bracket for 125 130

preventing reverse movement of the bifurcated wedge.

6. In combination with a bearing box and a frame in which said box is slidably mounted, a mechanism for automatically taking up wear in said bearing, comprising a bearing wedge adjustably mounted in said frame, a bracket detachably secured to said frame, a ratchet plate mounted in said bracket, a pair of auxiliary wedges, one wedge of said pair connected to said bearing wedge, the other wedge of said pair having ratchet teeth adapted to cooperate with said ratchet plate, a rod detachably connected to said last-named wedge and spring means embracing said rod for maintaining said auxiliary wedges in operative position.

7. In combination with a bearing box and a frame in which said box is slidably mounted, a mechanism for automatically taking up wear in said bearing comprising a bearing wedge adjustably mounted in said frame, a bracket secured to said frame, a pair of auxiliary wedges, means detachably connected to said bearing wedge for adjustably supporting one of said auxiliary wedges, a rod detachably connected to the other of said auxiliary wedges extending through a recess formed in said bracket, spring means pressuring said rod in one direction and a ratchet mechanism for preventing movement of said rod in reverse direction.

8. In combination with a bearing box

and a frame in which said box is slidably mounted, a bearing wedge adjustably mounted in said frame and means for adjusting the position of said wedge comprising a rod detachably connected thereto and extending through an aperture formed in said frame, a wedge member adjustably secured to said rod below the frame, a bracket depending from said frame, a bifurcated wedge mounted in said bracket and embracing said rod, spring means for maintaining said bifurcated wedge in operative contact with said wedge member, and ratchet mechanism for locking the bifurcated wedge from movement in one direction.

9. In combination with a bearing box and a frame in which said box is slidably mounted, an adjustable bearing wedge mounted in the frame, a bracket depending from the frame, mechanism mounted in said bracket for controlling the position of said bearing wedge comprising cooperating auxiliary wedges, and a spring-pressed rod extending through the bracket whereby relative positions of the auxiliary wedges may be readily ascertained by visual inspection.

In testimony whereof I have hereunto set my hand in presence of two subscribing witnesses.

JAMES EDWIN McDANIEL.
